TYPOGRAPHICAL SLUG CASTING MACHINE

Arthur Staniland Hayward and Victor Dougall,
Altrincham, England, assignors to Linotype
and Machinery Limited, London, England

Application August 3, 1936, Serial No. 94,001
In Great Britain August 14, 1935

6 Claims. (Cl. 199—51)

This invention relates to typographical slug casting machines such as those known commercially under the registered trade-mark "Linotype", and more particularly to machines provided with quadding and centring attachments, whereby either or both of the vice jaws (between which a line of composed matrices is clamped during the casting operation) is or are automatically moved inwardly to close on to a line 10 of less length than that for which the jaws are set.

In mechanism of this kind it has heretofore been proposed positively to move the jaws outwardly to a predetermined extent after they have 15 been closed on to the line and before justification takes place, or to permit the jaws to move outwardly to a limited extent under the expanding influence of the spacebands in the line during justification to provide for spreading of the line by a predetermined amount, or to a predetermined length.

With these known arrangements, however, excessive justification may take place before the line is filled out to the length determined by the 25 outward movement of the jaws, especially with lines considerably shorter than the desired length and containing few spacebands.

The object of the present invention is to provide means whereby the justifying action of the spacebands is itself limited when such lines are 30 to be centred or quadded, while permitting full justification to be effected when the quadding attachment is out of operation.

With this object in view, the invention consists 35 in a typographical slug casting machine embodying means for quadding or centring the matrices, wherein are provided means for limiting the movement of the justification bar which are set for operation by means associated with the quadding or centring devices, and become operative 40 when the movement of the jaw control rod exceeds a prearranged amount.

The invention will be readily understood from 45 the following description of two forms, given by way of example, which it may assume, and this description will be more conveniently followed by reference to the accompanying drawings, wherein:

Figures 1 and 2 represent, in front and side 50 elevation respectively, a machine incorporating the invention;

Figures 3 to 6 represent details thereof in larger scale, and

Figures 7 and 8 represent, respectively in front

and side elevation, a machine incorporating another form of the invention.

According to one constructional form of the invention, shown in Figures 1 to 6, the justification limiting stop is in the form of a spring controlled latch *a* turning about a fixed pivot into and out of engagement with a slot or recess *b* in each of the two rods *c* and *d*, by which the justification bar is actuated. The latch *a* is normally held in inoperative position against the action of its spring *e* by a bolt *f* which is moved out of the path of the latch when the quadding attachment is set for operation. As shown, the bolt *f* is actuated by links *g* connected with the control lever *h* of the quadding attachment, one of which links rides in an inclined slot *i* in the head of the bolt to raise or lower it when the lever *h* is moved. When the bolt *f* has been lifted, the latch *a* is held in inactive position by a regulating catch *k* adjustably secured to the jaw control rod *l*, the movement of which is dependent upon the length of the line against which the line clamping jaws are closed, so that by adjustment of the regulating catch *k* up or down relatively to the said control rod *l* the justification stop latch *a* can be brought into action when the jaws are closed on to a line of any given length. Thus, when the machine is set for quadding or centring, the justification stop may be automatically brought into the active 30 position when a line is presented between the jaws, in the event of such short line being less than the pre-arranged working measure by an amount exceeding a predetermined limit.

The operation will become clear by reference 35 to Figures 3 to 6, wherein Figures 3 and 5 represent in plan the latch *a* and associated elements respectively in the inoperative and operative positions, while Figures 4 and 6 represent respectively side sectional elevations of the settings shown 40 in Figures 3 and 5.

In a modification of the invention shown in Figures 7 and 8, the control lever *m* for the quadding setting has on the same shaft *n* a cam *o*. On a separate parallel shaft *p* are secured two 45 levers *r* and *s*, the latter being connected by links *t* to another short shaft *u* carrying an L-shaped stop member *v*. A spring *w*, extending between the frame of the machine and one of the links *t*, urges the arm *s* and its shaft in a 50 counterclockwise direction as shown in Figure 8, but such movement is prevented by contact of the adjustable screw *x* on lever *r* with the cam *o*, when the lever *m* is set in the position shown in Figure 8 holding the quadding devices inoperative. 55

tive. With this setting the stop member v is held out of the path of a roller y on the justification rod z , and full justification is therefore possible.

Also secured to the shaft p is an arm a^1 having a pin b^1 adapted to ride on a collar c^1 adjustably secured to the jaw control rod d^1 . When the control rod d^1 is in its uppermost position, and the jaws are thus open, the collar c^1 holds the arrangement of levers and links in the positions shown in Figure 8, independently of whether or not the cam o is set to hold the screw x . When, however, the control rod descends to close the jaws this restraint is removed, and, provided the cam o has been released from the screw x (which, as explained, occurs when the jaws are set for quadding or centring by means of the lever m), the pin b^1 follows the collar c^1 under action of the spring w and the linkage system is moved to bring the stop member v in the path of the roller y on the justification rod z , whereby the movement of the justification rod is limited.

By adjustment of the position of the collar c^1 on the control rod d^1 the initial position of the stop v can be modified, so that by this means the amount of movement of the rod d^1 necessary before the stop v is in its operative position can be adjusted.

It must be understood that the invention is not restricted solely to the details of the forms described above, which may be modified as desired under various conditions and requirements which have to be fulfilled without departing from the scope of the invention.

Having described our invention, we declare that what we claim and desire to secure by Letters Patent is:—

1. A typographical slug casting machine comprising matrix-clamping jaws and a control rod therefor, means for conditioning the control rod for a quadding or centring operation of the jaws, a device for justifying the matrix line, means for limiting the movement of said justifying device, and means associated with said conditioning means whereby said limiting means are set, in order to operate when the movement of said jaw control rod exceeds a prearranged amount.

2. A typographical slug casting machine comprising matrix-clamping jaws and a control rod therefor, means for conditioning the control rod

for a quadding or centring operation of the jaws, a device for justifying the matrix line, a stop member adapted to engage, and thereby limit the movement of said justifying device, and means to actuate a part normally holding said stop member out of operation and thereby release said stop, said actuating means being governed by the control rod conditioning means.

3. A typographical slug casting machine comprising matrix-clamping jaws and a control rod therefor, means for conditioning the control rod for a quadding or centring operation of the jaws, a device for justifying the matrix line, means for limiting the movement of said justifying device, means associated with said jaw control rod adapted to hold said limiting means out of operation until movement of said control rod exceeds a prearranged amount, and additional means governed by the control rod conditioning means for also holding the limiting means out of operation.

4. A typographical slug casting machine according to claim 3, wherein said means associated with the jaw control rod are adjustable to allow alteration as desired of the necessary amount of preoperative movement of said control rod.

5. A typographical slug casting machine comprising matrix-clamping jaws and a control rod therefor, means for conditioning the control rod for a quadding or centring operation of the jaws including a setting lever therefor, a device for justifying the matrix line, a spring-urged pivoted lever adapted to engage with said justifying device, and a catch normally holding said spring-urged pivoted lever out of engagement with said justifying device, but releasable upon operation of said quadding and centring setting lever in order to permit engagement of said spring-urged lever with said justifying device.

6. A typographical slug casting machine according to claim 5, comprising a stop member adjustably mounted on said jaw control rod, adapted to hold said spring-urged lever out of engagement with said justifying device, even after it is released by operation of said quadding and centring setting lever, until movement of the jaw control rod has exceeded a prearranged amount.

ARTHUR STANILAND HAYWARD.

VICTOR DOUGALL.
